C. L. HEISLER

BELL

Filed Sept. 27, 1923

Inventor :
Charles L. Heisler,
Alfred E. Baber
His Attorney.

UNITED STATES PATENT OFFICE.

CHARLES L. HEISLER, OF SCHENECTADY, NEW YORK.

BELL.

Application filed September 27, 1923. Serial No. 665,205.

To all whom it may concern:

Be it known that I, CHARLES L. HEISLER, a citizen of the United States, residing at Schenectady, in the county of Schenectady 5 and State of New York, have invented certain new and useful Improvements in Bells, of which the following is a specification.

The present invention relates to bells and particularly to bells which are required to 10 be made of bell-metal in order to obtain the required quality and duration of tone. As is well-known, bell-metal is an alloy composed of copper and tin. It is a species of bronze and is peculiarly adapted for bells 15 because of its hardness and sonorousness.

It is the common practice in manufacturing bells to cast them from bell-metal and afterward machine them on their outer and inner surfaces to give the desired finish and 20 exact dimensions. This means that the entire bell is made from bell-metal which metal is relatively costly and also that there is considerable finishing to do.

The object of my invention is to provide 25 an improved bell structure which without sacrificing any of the benefits and advantages of a bell made of bell-metal can at the same time be manufactured at a lower cost.

For a consideration of what I believe to 30 be novel and my invention, attention is directed to the accompanying description and the claims appended thereto.

In the drawing the figure is a side elevation partly in section of a bell embodying 35 my invention.

Referring to the drawing, 1 indicates the bell yoke, 2 the barrel or crown, 3 the sound bow or rim, 4 the clapper or tongue, and 5 the clapper bolt, these being the usual 40 parts of a bell.

According to my invention I form the barrel or crown of the bell from a metal less costly than bell metal and attach to such barrel or crown a sound bow or rim 45 of bell-metal. Preferably I form the barrel or crown of pressed steel of suitable thickness although it may be formed of any other suitable metal. The sound bow or rim which as already stated is formed from bell- 50 metal, may be cast directly to the lower edge of the barrel or crown or it may be cast separately and then attached to the barrel or crown by suitable means such as by fusion of metal, for example, by brazing or 55 welding. In any event, I prefer to form the sound bow by centrifugal casting so as to

obtain a dense metal as a denser metal improves the tone and wearing qualities.

In the drawing, the barrel or crown 2 is shown as being formed of pressed steel and 60 has the sound bow cast directly on its lower edge, such edge being provided with openings 6 through which metal may flow to firmly fix the sound bow to the barrel.

For attaching the barrel to the yoke I 65 provide a hollow ear or tang 7 on top of the barrel which fits into the opening or socket 8 in the yoke. Ear 7 and opening 8 are tapered as shown and for drawing the ear up into the opening and holding it I provide a tapered sleeve or plug 9 which surrounds bolt 5 and rests at its lower end on bolt head 10. When the nut on bolt 5 is screwed down bolt 5 draws sleeve 9 up into ear 7 and at the same time draws the ear 75 up into opening 8. The ear is thus tightly clamped in the yoke. Suitable clearance spaces 11 are provided to permit the parts to be drawn together.

By the above-described arrangement I effect a saving in the cost of the material for a bell in that a considerable portion of the bell is formed of a metal cheaper than bell-metal. Also I effect a saving in cost in that the pressed steel barrel or crown requires no 80 machine work for finishing it and may be manufactured in quantities at a low manufacturing cost. The quality of tone of a bell depends not only upon the composition of the metal from which the sound bow is 85 made but also to a considerable extent upon its shape and the proportions between its height, width and thickness. By making the barrel or crown of pressed steel it can be easily accurately dimensioned in the first 90 instance to give the desired proportions so there is left only the finishing of the sound bow to bring the bell to dimension. A bell made in accordance with my invention I have found to have a tone equal in quality 95 to that of a bell formed entirely of bell-metal, this being due to the fact, I believe, that so far as the material of the bell is concerned, the quality of the tone is governed almost entirely by the character of the metal 100 in the sound bow.

An application of my invention and one to which it is well adapted is that of making bells for railroad locomotives, although it is not limited to this use.

In accordance with the provisions of the patent statutes, I have described the principle

ple of operation of my invention, together with the apparatus which I now consider to represent the best embodiment thereof, but I desire to have it understood that the apparatus shown is only illustrative and that the invention may be carried out by other means such as come within the scope of the appended claims.

What I claim as new and desire to secure by Letters Patent of the United States is:—

1. A bell having its barrel formed of one material and its sound bow of a different material.

2. A bell having its barrel formed of a ferrous metal and its sound bow of bell-metal.

3. A bell having its crown formed of pressed steel and its sound bow of bell-metal.

4. In a bell structure, a yoke having an opening, a barrel of pressed metal having an ear which fits into the opening, a sleeve in the ear, a clapper bolt which extends through the sleeve and clamps the ear between the sleeve and the yoke, and a sound bow of bell-metal attached to said barrel.

5. In a bell, a crown formed of a ferrous material, and a rim formed of centrifugally cast bell-metal.

In witness whereof, I have hereunto set my hand this 25th day of September, 1923.

CHARLES L. HEISLER.
